UNITED STATES PATENT OFFICE.

ELIZA JANE LYNCH, OF NEW YORK, N. Y.

DESIGN FOR A CHILD'S BONNET.

SPECIFICATION forming part of Design No. 18,757, dated November 27, 1888.

Application filed March 21, 1887. Serial No. 231,781. Term of patent 3½ years.

To all whom it may concern:

Be it known that I, ELIZA JANE LYNCH, of New York, in the county of New York, and in the State of New York, have invented a certain new and useful Design for a Child's Bonnet; and I do hereby declare that the following is a full, clear, and exact description thereof, reference being had to the accompanying drawing, in which is shown in side elevation a bonnet of my design.

The principal feature of my design consists in the general shape of the bonnet, its front being composed of a part, A, which extends from the bottom at each side upward to and over the top, and is ornamented by parallel lines of narrow plaits *a*. The back and crown is composed of a piece, B, that extends from the rear edge of said front rearward and upward, and has its lower rear portion ornamented by narrow vertical plaits *b*, which terminate at a substantially horizontal ornamental band, *b'*. Above said band said part has a rounded or dome shape, as shown, and is ornamented by means of a number of narrow plaits, *b''*.

Around the front and bottom edge of the bonnet is a ruffle, C, while other ruffles, D, are arranged upon the front A in rear of the ruffle C, and extend up each side and over the top of said front. 30

Having thus described my invention, what I claim is—

The design for a bonnet, consisting of the front A, ornamented by the parallel plaits *a*, the back B, having a rounded or dome-shaped 35 upper part and ornamented by the vertical parallel plaits *b* at its lower part and ornamental stitching *b'* at the upper edge of said plaits, and the front and bottom edges of the bonnet being ornamented by the ruffles C and D, as shown. 40

In testimony that I claim the foregoing I have hereunto set my hand this 19th day of March, 1887.

ELIZA JANE LYNCH.
